UNITED STATES PATENT OFFICE.

HARRY D. GIBBS, OF SAN FRANCISCO, CALIFORNIA, DEDICATED, BY MESNE ASSIGNMENTS, TO THE PEOPLE OF THE UNITED STATES.

PROCESS FOR PURIFYING ANTHRACENE PRESS CAKE.

No Drawing.

Application filed February 8, 1919. Serial No. 275,904.

(FILED UNDER THE ACT OF MARCH 3, 1883, 22 STAT. L. 625.)

To all whom it may concern:

Be it known that I, HARRY D. GIBBS, a citizen of the United States of America and an employee of the Department of Agriculture, residing in the city of San Francisco, county of San Francisco, State of California, have invented a new and useful Process for Purifying Anthracene Press Cake.

This application is made under the act of 10 March 3, 1883, chapter 143 (22 Stat. 625), and the invention herein described and claimed may be used by the Government of the United States or any of its officers or employees in the prosecution of work for 15 the Government or any person in the United States, without payment to me of any royalty thereon.

The object of my invention is to purify anthracene, carbazole, phenanthrene and other useful compounds found in anthracene press cake and separate them from each other in a higher degree of purity and thus render these valuable compounds available in a sufficient degree of purity for treatment 20 in various chemical ways to produce intermediate compounds and dyes from them.

The process of purifying anthracene, carbazole and phenanthrene has heretofore been carried out by means of solvents that 25 dissolve one or more of the constituents more or less completely, thus enabling the separation by solution and fractional crystallization. The process is slow, cumbersome and entails a considerable loss of valuable solvents. My process requires no solvents, is inexpensively operated and produces the desired substances in a higher state of purity.

In describing my process I shall, as an example, describe the several steps of the 30 complete process, it being understood that while all of the steps are not independently novel they have not been heretofore employed in connection with the novel steps of the process, for which reason they have 35 not satisfactorily accomplished the results attained in the practice of my invention.

It is well known that the constituents of anthracene press cake have individual melt-

ing, subliming and boiling points. The figures, stated in degrees centigrade, found in 50 the literature for the melting and boiling points of a number of these are given as follows:

Compound.	For- mu-la.	Melting point.	Boiling point.	55
Acenaphthene.....	C ₁₂ H ₁₀	95°	280°	
Phenanthrene.....	C ₁₂ H ₁₀	100°	340°	
Acridine.....	C ₁₃ H ₉ N	107°	Above 360° (Above 360°)	
Fluoranthrene.....	C ₁₅ H ₁₀	109°	217° at 30 mm. pres.	60
Fluorene.....	C ₁₃ H ₁₀	113°	295°	
Pseudophenanthrene.....	C ₁₆ H ₁₂	115°	Above 360°	
Pyrene.....	C ₁₆ H ₁₀	149°	Above 360°	
Anthracene.....	C ₁₄ H ₁₀	{ 213°, also given as 216.5°	{ 360°, also given as 351°	
Carbazole.....	C ₁₂ H ₉ N	238°	351.5°	65
Methylanthracene.....	C ₁₅ H ₁₂	200°	Above 360°	
Chrysene.....	C ₁₈ H ₁₂	250°	448°	

I have reason to believe that in many cases the figures are not accurate, but they will do to illustrate the different behavior of 70 these compounds.

When a current of heated air is being charged with these constituents the most volatile will be taken up in the largest proportion and when the charged air is cooled 75 the least volatile will separate out first. It is also true that some of these constituents separate out in so fine a state of division that they are carried suspended in the air for a longer time than those constituents 80 that are denser. This is well known.

I have discovered that when a current of air so charged with the substances is caused to move through small orifices the least volatile constituents separate and aggregate 85 on the edges or against the orifices. Crystallization and separation from the vapor phase is thus assisted by the orifices and the passage of the gas through the orifices. These orifices may be arranged in large numbers in approximately the same plane in a sheet, plate or screen composed of metal, 90 fiber or other substance, or the aggregation of orifices may be attained by use of gauze, screen, cloth made of wire, or woven or spun 95 fibers.

I have also found a multiple arrangement of these planes of orifices on the plan of connecting rooms or compartments offer the additional advantage of forming a temperature gradient varying from the highest temperature where the gas stream enters to the lowest temperature in the farthest compartment, the fall in the temperature of the gases being quite sharp as they pass through the orifices or just after passing through the orifices. This temperature gradient between the compartments is caused by the removal of heat from the gases as they pass through the orifices by conduction and radiation.

I do not wish to confine myself to the use of these orifices or screens in multiple in the same plane, but these orifices may be arranged in circles, in spheres, concentric or otherwise, or any figure of revolution or in warped or bent surfaces. I have found that in various cases one arrangement possesses an advantage over other arrangements depending upon the character and state of the material which is being separated and also depending on the size and capacity desired in the apparatus.

I do not wish to confine myself to the use of atmospheric air for the reason that in some cases it is advisable to use furnace gases, flue gases, carbon dioxide or other gases.

The separation of carbazole may be facilitated, if desired, by taking advantage of the fact the carbazole is an amino acid and unites with metals to form salts. Very strong caustic soda or potash (sodium hydroxide or potassium hydroxide), or metallic sodium may be added to the press cake and melted with it. The sodium or potassium salt of carbazole is thus formed and this is not volatilized in the current of heated air. Since a compound of this nature is hydrolyzed by water given caustic alkali and carbazole the air should be dried and every precaution taken to keep the amount of moisture present in the melt pot at a minimum. The salt of carbazole in the melt may be purified in various ways, preferably by neutralization with acid and subliming the carbazole.

An example of the working of this process with the use of alkali is given in the following figures compiled from a factory run and this may be regarded as embodying the essentials of the preferred procedure. However, I do not wish to be confined to this procedure for in very large scale operations various modifications will be necessary.

Anthracene press cake was mixed with 5 per cent caustic soda and heated in a closed iron vessel to 475° F. and a current of air run over it at the rate of 3 cubic feet per minute for each square foot of screen surface separating the first compartment of the condenser from the second. The air current

was conducted into the first compartment of the condensing apparatus consisting of a series of compartments separated from each other by screen made of wire cloth of about one-half inch mesh. The temperature of the gas stream entering the first compartment was about 200° C. and the temperature of this compartment should be maintained above 150° C., and preferably so high as 200° C., and in some cases to 250° C.

In large scale operations I consider it an advantage to dispense with the use of alkali mixed with the press cake and feed the press cake molten into the moving air current where it may be distributed by means of baffle plates.

The analysis of the anthracene press cake showed approximately 20 per cent anthracene, 25 per cent carbazole, 20 per cent oil and moisture, and the remainder the other constituents usually present, principally phenanthrene.

The condensed material was collected from the various rooms and analyzed. The first and hottest compartment showed 43 per cent anthracene and 18 per cent carbazole, the middle compartments 25 per cent anthracene and 12 per cent carbazole, and the last or coolest compartment approximately 12 per cent anthracene, 8 per cent carbazole, and the remainder of the 100 per cent mostly phenanthrene.

A second treatment of the material from the first or hottest compartment without using caustic alkali to hold back the carbazole from subliming from the melting pot gave:

First compartment—carbazole 80 to 83%.

Second compartment—anthracene 75%.

Third compartment—almost all phenanthrene.

A third or a fourth treatment of the various fractions is advisable when further purification of the material is desired.

The quantities of material purified in a given time depend upon the size and arrangement of the apparatus, the volume of the air employed, and the character of the material.

The air current may be charged with the volatile constituents in various ways, other than described above, for example, by feeding the solid or molten material into the air stream or passing the air stream over or through baffles containing the material to be volatilized.

The material collecting on the screen or around the orifices may be removed by shaking or jarring the screens, or by scrapers or brushes, operated by hand intermittently or continuously by mechanical devices.

The material falling from the screens and condensing in the various compartments may be removed from time to time by means of chutes in the bottom of the compartment or

it may be scraped from the floor of the compartments and removed through doors placed in the side or bottom walls.

Having now fully described my invention, what I claim and desire to protect by Letters Patent is—

1. The process of purifying carbazole, anthracene and phenanthrene by fractional condensation from a moving gas stream, collecting these and other substances in compartments separated from each other by partitions containing a multiplicity of orifices of such size as not to act as a dust catcher.
- 15 2. The process of purifying carbazole, anthracene and phenanthrene by fractional condensation from a moving gas stream, collecting these and other substances in compartments separated from each other by partitions composed of cloth with orifices of such size as to permit dust to pass therethrough freely.
- 20 3. A process of treating anthracene press-cake, which comprises heating the same with an alkali to convert the carbazol present into a salt, then heating further to a temperature

sufficient to fractionally sublime anthracene and other materials, and collecting such sublimed materials.

4. In the fractionation of crude anthracene press-cake, the steps of treating with an alkali, and thereafter heating to about 200° C. in contact with a flowing gas current, whereby substances other than carbazol are vaporized, and carried along by said gas current, and thereafter gradually cooling said gas current whereby such vaporized substances are deposited in the solid state.

5. The improvement in the recovery of methyl anthracene, phenanthrene and anthracene, which comprises heating to about 200° C. in a flowing gas current, a mixture comprising such materials, and gradually cooling the said gas current.

In testimony whereof, I affix my signature in the presence of two subscribing witnesses.

HARRY D. GIBBS.
